UNITED STATES PATENT OFFICE.

WILLIAM N. BUTTON, OF BRISTOL, RHODE ISLAND, ASSIGNOR OF ONE-HALF TO
TERRENCE McCARTY, OF BRISTOL, RHODE ISLAND.

SHOE-BUCKLE.

1,097,296.

Specification of Letters Patent. Patented May 19, 1914.

Application filed May 15, 1913. Serial No. 767,750.

To all whom it may concern:

Be it known that I, WILLIAM N. BUTTON, a citizen of the United States, residing at Bristol, in the county of Bristol and State 5 of Rhode Island, have invented a new and useful Improvement in Shoe-Buckles, of which the following is a specification.

This invention relates to certain new and useful improvements in shoe buckles, and 10 pertains more particularly to the clasp-structure.

The primary object of the invention is to provide means for preventing accidental unlocking movement of the clasp, when the 15 latter is in operative or closed position, and further to provide a novel form of clasp and means for movably supporting same.

Still further, the invention aims to provide a novel, improved and simplified form 20 of clasp.

In the drawings Figure 1 is a front elevation of the invention. Fig. 2 is an edge elevation. Fig. 3 is a perspective view of the clasp in open position. Fig. 4 is a view similar to Fig. 3, showing the clasp in locked or closed position, and Fig. 5 is an enlarged rear plan view of the clasp showing the same in locked position.

The eye member 1 is formed with the 30 usual number of openings to receive the clasp member, and is of curved form. The clasp member consists of a base portion that is formed of a section of sheet metal which is doubled upon itself to provide sockets 2, 35 each of the doubled portions being formed with a slot 3, which slots register to provide an opening to enable the base to be fastened to one side of a shoe upper. The doubled part is cut away at its central portion at 40 so as to leave a space for a purpose now to be set forth.

The clasp member proper is formed of wire which is bent to have a bill 5, which bill is formed by doubling over the wire, 45 the ends of the wire being extended outwardly at 6 and received in the sockets 2, the extremities of the said ends being curved and turned inwardly and flattened at 7 to form fingers which are adapted to snap over 50 the base member, for which purpose the bill

is formed of metal that is possessed of spring properties. When the bill is in locked position the fingers 7 extend on the rear or inner face of the base, while the bill extends on the outer or front face of the base. The 55 free ends of the base member are preferably separated at 8 so as to allow the base to engage on opposite faces of one side of the shoe upper. The space 4 allows the projecting ends 6 of the clasp to be received in the 60 sockets 2 and moved relative to the latter.

In operation the clasp member is first moved outwardly so as to cause the fingers 7 to occupy the position depicted in Fig. 3, whereupon the bill is engaged through one 65 of the slots of eye member 1, after which the clasp is moved to the position shown in Fig. 4, in which movement the fingers 7, due to the spring nature of the clasp, ride over the side edges of the base and are then 70 snapped so as to engage on the rear face of the base in the position shown in Fig. 5, whereby it will be seen that the clasp is held against accidental movement.

Having thus described my invention, I 75 claim as new and desire to secure by Letters Patent;—

1. In a shoe buckle, a base member formed of sheet metal doubled over and centrally cut-away at its doubled edge to form a pair 80 of spaced sockets, a clasp member formed of a piece of spring wire doubled over to form a bill the base of which is received in said cut-away part of the base member, the free end portions of the bill being extended 85 outwardly and passed through said respective sockets to provide journals and extending beyond the outer side edges of said base member and then curved inwardly and flattened at their extremities and adapted 90 to snap over said edges of the base member.

2. In a shoe buckle, a base member having a pair of sockets, a wire bill having its ends extended outwardly and passed through said respective sockets to provide journals and 95 extending beyond the outer side edges of said base member and then returned inwardly and adapted to have their extremities snap over said side edges of the base member.

3. In a shoe buckle, a base having bearings, a wire bill having its ends provided with journals which extend through said bearings, and integral extensions on the 5 journals having their free extremities adapted to snap over edge portions of the base.

In testimony whereof I have signed my name to this specification in the presence of two subscribing witnesses.

WILLIAM N. BUTTON.
